SASH STOP

Filed Feb. 21, 1930

UNITED STATES PATENT OFFICE

GILBERT S. KREIDER, OF KANSAS CITY, MISSOURI, ASSIGNOR, BY DIRECT AND MESNE ASSIGNMENTS, TO HERMAN COPAKEN, OF KANSAS CITY, MISSOURI

SASH STOP

Application filed February 21, 1930. Serial No. 430,391.

My invention relates to improvements in sash stops.

One of the objects of my invention is to provide a novel sash stop adapted to be fastened to the upper of two associated sliding window sashes, which permits a limited opening movement of either sash, which can not be operated from the exterior so as to permit any further opening of the sashes, and which can only be operated to release the sashes only from the interior and then only when the sashes are closed or nearly so.

My invention provides further a novel sash stop, which is simple, cheap, strong, durable, not likely to get out of order, which can be readily and quickly attached to a window sash of usual construction, which is difficult to feloniously operate from the exterior, and which is efficient in its operation.

The novel features of my invention are hereinafter fully described and claimed.

In the accompanying drawings, which illustrate the preferred embodiment of my invention,

Fig. 1 is a reduced front elevation of my improved sash stop shown attached to an upper sash and engaged with a lower associated sliding sash.

Fig. 2 is an enlarged front elevation of my improved stop, the catch being shown in solid lines in the stop position, and being shown in dotted lines in the release position.

Fig. 3 is a view similar to Fig. 2, the catch being shown swung out of the path of the lower sash.

Fig. 4 is an enlarged section on the line 4-4 of Fig. 1.

Fig. 5 is a section on the line 5-5 of Fig. 2.

Fig. 6 is a front elevation of the catch.

Fig. 7 is an edge elevation of the same.

Fig. 8 is a front elevation of the lower part of the supporting plate, and the catch shown moved downwardly past the release position.

Fig. 9 is an enlarged vertical sectional view of the upper part of the supporting plate and a portion of the catch.

Similar reference characters designate similar parts in the different views.

My improved sash stop is provided with a support, comprising, as shown, a metal plate

1 which is adapted to be fastened to the inner side of one of the stiles of an upper sash 2, which is slidably mounted in a window frame 3 and with which is associated a sliding lower sash 4 mounted, as usual, in the frame 3. 55

The upper and lower portions of the supporting plate 1 are respectively provided with holes 5 adapted to receive respectively two screws 6, Figs. 4 and 8.

The supporting plate 1 is provided with 60 catch guiding means, which, as shown, comprises two vertical parallel guides 7 and 8. The guide 7 is tubular, is disposed at one vertical edge of the plate 1 and is provided at its inner side with a longitudinal slot 9, in 65 which is adapted to be slidably mounted a catch 10, one vertical edge portion of which is formed into a vertical barrel 11 slidably mounted in the tubular guide 7.

The guide 8 is formed in the plate 1 so as 70 to have its inner edge raised for nearly the full length of the guide 8 above the surface of the plate 1, thus providing a slot 12 adapted to have extended therethrough and slidable therein a projection 13 at the vertical 75 edge of the catch plate 10 opposite to the edge having the barrel 11.

The upper end of the catch 10 has a U shaped projection 14, which extends, when the catch 10 is slidably engaged with the 80 guides 7 and 8, into the path of the lower sash 4.

The supporting plate 1 is fastened to the lower end of the stile of the upper sash, the catch 10 being normally disposed, when the 85 sashes are both closed, in the lowermost position, shown in Fig. 8.

When the lower sash is lifted, or the upper sash is lowered, the top rail of the lower sash will strike the projection 14 of the catch 10 90 and will lift the latter in the guides 7 and 8 until the catch reaches the upper limit of its movement, which will be when the projection 14 strikes an abutment comprising the upper end of the guide 8, or against the upper screw 95 6, when the latter has a projecting head, as shown.

The movement of both sashes will thus be limited. The catch can not be released from the lower sash until both sashes are closed or 100

nearly so. To release the lower sash, to permit of it being raised higher than the stop position, shown in Figs. 1 and 2, the sashes are closed. The catch 10 is then slid to the release position shown in dotted lines in Fig. 2, in which position the projection 13 on the edge of the catch 10 will register with a notch 15 in the inner edge of the guide 8. In this release position the catch 10 may be swung on the guide 7 to the position shown in Fig. 3 and in dotted lines in Fig. 4, in which position, the stop projection 14 will be clear as will the body of the catch 10 of the path of the top rail of the lower sash 4, so that the latter can be raised within the full range of its movement or the upper sash 2 may be similarly lowered.

To enable the catch to swing out of said path, as described, the conformation of the guide 7 provides therein two notches 16 having between them a tongue 17, the latter being adapted to enter a slot 18 in the catch body 10. The barrel 11 of the catch 10 is slightly shorter than the distance between the top of the upper notch 16 and the lower end of the lower notch 16.

When the catch 10 is in the lowermost position, shown in Fig. 8, its lower end will rest against the screw 6. In this position the catch will be below the release position shown in dotted lines in Fig. 2, and the guides 7 and 8 will prevent it being swung out of the path of the top rail of the lower sash 4.

When it is desired to raise the lower sash higher than the stop position, the operator, from the inside, lifts the catch 10 from the position shown in Fig. 8 to the release position, shown in dotted lines in Fig. 2, and then swings the catch 10 to the position shown in Fig. 3 and in dotted lines in Fig. 4.

If the lower sash 4 is lifted from outside to bring the catch 10 to the release position, the lower sash will cover the catch 10 below the projection 14, so that the catch can not be swung out of the path of the lower sash.

When the sashes are closed, the operator swings the catch 10 from the position, shown in Fig. 3 and in dotted lines in Fig. 4, to the release position shown in dotted lines in Fig. 50 2, in which latter position, the projection 13 will enter the notch 15, after which the projection 13 and the body of the catch can be respectively slid upwardly or downwardly in the slots 12 and 9.

As the catch 10 can not be moved out of the path of the lower sash unless both sashes are closed or nearly so, no opportunity is afforded an outsider to release the lower sash 4 from the catch.

To prevent the catch 10 from being accidentally forced out of the guide 7 at the upper end thereof, in case that the projection 13 is not entered into the slot 15 and engaged with the guide 8, there is provided in the upper part of the guide 7 an inwardly extend-

ing projection 19 forming an abutment which is adapted to be struck by the barrel 11 of the catch 10, thus preventing further upward movement of the catch, Fig. 9.

I do not limit my invention to the structure shown and described, as many modifications, within the scope of the appended claims, may be made without departing from the spirit of my invention.

What I claim is:—

1. In a sash stop, a support having an abutment and adapted to be fastened to one of two associated sliding sashes and having a tubular guide, and a catch carried by said support and slidably fitted in said tubular guide and movable in the path of said other sash from a release position to a stop position against said abutment in which stop position it is adapted to engage said other sash and permit but a limited opening movement of either sash, and movable, only when sashes are closed or nearly so, from said stop position to said release position, said catch pivotally engaging said tubular guide at said release position enabling said catch to swing thereon out of said path, said tubular guide alone holding said catch from moving out of said path excepting when said catch is in said release position.

2. In a sash stop, a support having an abutment and adapted to be fastened to one of two associated sliding sashes having two parallel guides, and a catch carried by said support and slidably engaging said guides and movable in the path of said other sash from a release position to a stop position against said abutment in which stop position it is adapted to engage said other sash and permit but a limited opening movement of either sash, and movable, only when both sashes are closed or nearly so, from said stop position to said release position, and in said release position being disengaged from one of said guides and pivotally engaged with the other guide, said pivotal engagement with the latter permitting said catch to swing thereon out of said path, said guides alone holding said catch from moving out of said path excepting when the catch is in said release position.

3. In a sash stop, a support having an abutment and adapted to be fastened to one of two associated sliding sashes, having two parallel guides one of which is tubular, and a catch carried by said support and slidably engaging said guides and movable in the path of the other of said sashes from a release position to a stop position against said abutment in which stop position it is adapted to engage said other sash and permit but a limited opening movement of either sash, and movable, only when both sashes are closed or nearly so, from said stop position to said release position, and in said release position pivotally engaging said tubular guide and being disengaged from the other guide, said

5 pivotal engagement of said catch with said tubular guide at the release position permitting said catch to swing thereon out of said path, said catch being movable from said stop position past said release position when said sashes are fully closed, said guides alone holding said catch from moving out of said path excepting when in said release position.

10 4. In a sash stop, a support having an abutment and adapted to be fastened to one of two associated sliding sashes having two parallel guides, one of which is tubular and the other having a notch, and a catch carried by said support and slidably engaging said guides and movable in the path of the other of said sashes from a release position to a stop position against said abutment in which stop position it is adapted to engage said other sash and permit but a limited opening movement of either sash, and movable, only when both sashes are closed or nearly so, from said stop position to said release position, and in said release position pivotally engaging said tubular guide and adapted to swing thereon through said notch out of said path, and movable from said stop position past said release position when said sashes are fully closed, said guides alone holding said catch from moving out of said path excepting when said catch is in said release position.

15 5. A sash stop comprising a support having an abutment and adapted to be attached to the upper of two associated sliding sashes, and a catch reciprocal vertically on said support between an upper stop position against said abutment and a release position below and spaced from said abutment, and in said positions being in the path of the lower of said sashes, and in said upper position being adapted to engage the upper edge of said lower sash and limit the opening movement of either sash, and in said release position being movable to and from a position out of said path.

20 6. A sash stop comprising a support having an abutment and adapted to be attached to the upper of two associated sliding sashes, and a catch reciprocal vertically on said support between an upper stop position against said abutment and a release position below and spaced from said abutment, and in said positions being in the path of the lower of said sashes, and in said upper position being adapted to engage the upper edge of said lower sash and limit the opening movement of either sash, and in said release position being movable to and from a position out of said path, said support having means for engaging and holding said catch from moving out of said path excepting when said catch is in said release position.

25 7. A sash stop comprising a support having an abutment and adapted to be attached to the upper of two associated sliding sashes, and a catch reciprocal vertically on said

support between an upper stop position against said abutment and a release position below and spaced from said abutment, and movable to a position below said release position, and in said positions being in the path of the lower of said sashes, and in said upper position being adapted to engage the upper edge of said lower sash and limit the opening movement of either sash, and in said release position being movable to and from a position out of said path, said support having means for engaging and holding said catch from moving out of said path excepting when said catch is in said release position.

30 In testimony whereof I have signed my name to this specification.
